(57) **CLAIM**

I claim the ornamental design for a body-building machine, as shown and described.

DESCRIPTION

FIG. 1 is a front elevational view thereof.

FIG. 2 is a right side elevational view thereof.

FIG. 3 is a left side elevational view thereof.

FIG. 4 is a top plan elevational view thereof.

FIG. 5 is a bottom plan elevational view thereof.

FIG. 6 is a rear elevational view thereof; and,

FIG. 7 is a right perspective view of a body-building machine.
